UNITED STATES PATENT OFFICE

2,097,004

FLAGEOLET

Bernard E. Walberg, Worcester, Mass.

Application September 12, 1936, Serial No. 100,415

2 Claims. (Cl. 84—386)

This invention relates to a musical instrument of the flageolet type.

The principal objects of the invention are to provide a means whereby the tone of the flageolet can be changed by a half tone in a very simple manner; to provide a construction by which the mouthpiece will come back to normal after a half tone change has been made, and to provide a telescoping flageolet for increasing and decreasing the length of the air column at will.

Other objects and advantages of the invention will appear hereinafter.

Reference is to be had to the accompanying drawing, in which

Fig. 1 is a side view of a flageolet constructed in accordance with this invention with parts in section to show interior construction;

Fig. 2 is a plan of the flageolet;

Fig. 3 is a bottom plan thereof, and

Fig. 4 is a sectional view on the line 4—4 of Fig. 1.

It will be seen that the flageolet is made in accordance with the ordinary flageolet on the market having a main tube 10 with perforations 11 which are adapted to be stopped by the fingers to provide the desired notes. Preferably it has the usual thumb rest 12 on the bottom.

Secured on the tube 10 is a fixed tube 13. This tube carries a hollow projection 14 through which passes a slide 15 with a stop 16 on the end. This slide is provided with a spring 17 surrounding it and pressing the tube 13 and a circular band 18 away from each other. On the band 18 the slide 15 is firmly fixed. This band 18 has an opening 19 at the top and it is provided with two wings 20 at the edges of said openings to direct the air columns which, of course, come through the mouthpiece 21. This mouthpiece is mounted on a cylinder 22 which is telescopically connected with the member 13. The cylinder 22 is closed by a cork 23, this cork constituting the end of the flageolet and these three parts 21, 22, and 23 always being stationary with respect to each other.

The wings 20 direct the air currents from the

mouthpiece 21 and the impact of these air currents against a tip 24 produces the sound as in all flageolets.

In the use of this instrument, if it is desired to change the tone by a half tone the operator, holding the main tube 10 in his hands, brings the mouthpiece in his mouth and brings the tube 10 back so that the air column is shortened to make change of a half tone. A spring 17 moves the main tube toward the mouthpiece 10 until the stop 16 engages the projection 14, as shown in the drawing.

In the instrument shown, the maximum amount of motion is enough to change the sound by a half tone and that is the limit and also the ordinary action of this instrument. The different notes can be sounded and any one of them changed by a half tone in the manner set forth.

This constitutes an extremely simple means for changing the tone without the necessity of any hand manipulation and without having any expensive extra parts for making the change.

Having thus described my invention and the advantages thereof, I do not wish to be limited to the details herein disclosed, otherwise than as set forth in the claims, but what I claim is:

1. As an article of manufacture, a flageolet comprising a tube, a mouthpiece and a tip, said tube being movable with respect to the mouthpiece, a slide connecting the tube with the mouthpiece, and a spring on the slide for forcing the tube forward after it has been pushed toward the mouthpiece, to change the note by a half tone.

2. As an article of manufacture, a musical instrument of the flageolet type comprising a tube, a tip carried thereby, a mouthpiece movable with respect to the tube, a longitudinal slide connecting the tube with the mouthpiece, a spring on the slide for forcing the tube forward after it has been pushed toward the mouthpiece, and a stop at the end of the slide for limiting the telescoping action.

BERNARD E. WALBERG. 45
